United States Patent Office

Des. 186,132
Patented Sept. 15, 1959

186,132

PIPE WRENCH

Carlos V. St. Claire, San Bernardino, Calif.
Application April 27, 1959, Serial No. 55,676

Term of patent 14 years

(Cl. D54—16)

Figure 1 is a front left perspective view of a pipe wrench, showing my new design; and

Figure 2 is a front right perspective view thereof.

I claim:

The ornamental design for a pipe wrench, as shown.
